UNITED STATES PATENT OFFICE.

CLAUDE A. DUNN, OF DENVER, COLORADO, ASSIGNOR, BY DIRECT AND MESNE ASSIGNMENTS, TO THE AUTOMATIC RAILWAY SWITCH COMPANY, OF SAME PLACE.

RAILWAY-SWITCH.

SPECIFICATION forming part of Letters Patent No. 663,872, dated December 18, 1900.

Application filed December 11, 1899. Serial No. 739,998. (No model.)

To all whom it may concern:

Be it known that I, CLAUDE A. DUNN, a citizen of the United States of America, residing at Denver, in the county of Arapahoe and State 5 of Colorado, have invented certain new and useful Improvements in Railway-Switches; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

My invention relates to a combined railway-car switch and switch-throwing device operating from railway-cars; and the objects of my invention are, first, to provide a rail-switch for cars that can be operated from the platform of cars by the engineer or motormen; second, 20 to provide a switch that will clean out the dirt that accumulates between the tongue and the rail each time the switch-thrower passes through the switch; and, third, to provide a simple, durable, and easily-manipulated railway-switch. I attain these objects by the mechanism illustrated in the accompanying drawings, in which—

Figure 1 is a plan view of my improved switch, showing a portion of the switch-tongue. 30 Fig. 2 is a plan view of my switch, showing a complete switch. Fig. 3 is a side elevation of Fig. 1 with the guard-rail left off. Fig. 4 is a side elevation of the switch and its operating device and shows its application and 35 method of throwing the switch from the platform of a car. Fig. 5 is a side elevation of the switch-throwing plunger-rod. Fig. 6 is an end elevation of Fig. 4 with the return-spring and a fragment of the platform in place 40 around it. Fig. 7 is a section of the switch-lever and a section of a fragment of the switch-tongue and bed-plate, showing a modification of the switch-lever. Fig. 8 is a fragment of the switch-thrower, showing a modification of 45 the scraper; and Fig. 9 is a fragment of the switch-thrower, showing a modification of the switch-engaging wheel shown in Figs. 4 and 5.

Similar figures of reference refer to similar parts throughout the several views.

Referring to the drawings, the numeral 1

designates one T-rail, bent with the usual offset 2 to receive the end 3 of a switch-tongue 4, which is pivotally secured to the iron bed-plate 5. This bed-plate rests on the sleepers 6 in the usual manner. 55

7 designates the guard-rail.

In the end of the tongue I cut a slot 8 and preferably cut the lower part 9 of the end of the tongue 4 off a little shorter than the upper end 10. In this slot I pivotally secure by a 60 pin 11 one end of a lever 12, which is stepped and narrowed at this end to fit loosely in the slot. This lever is made a little narrower at its pivotal end than the end of the switch-tongue, so that it will not contact with the 65 side of the T-rail. From this point it broadens out and rests against the side of the rail just beyond the point of the tongue. From the point 13, where the lever contacts with the tongue, it narrows up on both sides to a com- 70 paratively thin blade 14, which extends to and lies against the guard-rail, its point being beveled equally from the center of the blade, which projects on a straight line with the pivotal center of the lever in the tongue. 75 The switch and switch-lever are shown in dotted lines in Fig. 1 switched against the guard-rail. Owing to the great length of the switch-rail and the scale of Fig. 1, the pivotal end of the switch is not shown, but is illus- 80 trated on a smaller scale in Fig. 2.

The switch-thrower comprises a rod 15, which extends down through the platform 16 of a car 17. The rod passes through a flange 18, which is secured to the floor of the plat- 85 form between the sills 19 of the platform. A spring 20 surrounds the rod, one end being attached to the rod below the flange, and the opposite end rests on the flange 21, which is secured to the under side of the sills of the 90 platform. The spring is arranged to normally hold the rod up away from the rail a few inches.

Upon the platform end of the rod a foot-disk 22 is secured, from one side of which a 95 short arm 23 extends, the end of which is preferably turned up in order that it may be more easily pressed against or struck with a side movement of the foot than the thin disk. The portion of the rod that depends below 100

the platform is narrowed to a thin blade 19^A to near its lower end, which should be elastic enough to spring easily several inches laterally of the car and rail in both directions.

5 To the flange 21 I secure a bracket 21^A, which is provided with a bifurcated end that straddles the blade portion of the rod, as shown in Figs. 4 and 6. The ends straddle the blade loose enough to allow the blade a little lateral play, just enough to allow the rod to be turned a little in either direction by the side pressure of the foot. The lower end of the rod has removably secured to it a yoke 24. To quickly and easily secure the yoke to the lower end of the rod, I make it with a shaft 25 projecting from the top of the yoke and make the end of the rod hollow and fit the shaft loosely in it, forming a shoulder at the base of the shaft for the end of the rod to rest 20 against. I then secure the two together by passing the bolts 26 through them.

Between the arms of the yoke I pivot, by a pin 27, a small wheel 28. Just above the wheel on the shaft of the yoke I secure a sleeve 29 by passing a bolt 30 through the sleeve and shaft. This sleeve forms part of a scraper 31, that curves down over and a little below the wheel 28 and is adapted to bear against and to scrape along the top of the bed-plate 30 as the switch-thrower passes through the switch.

The operation is as follows: The end of the switch-lever always lies against either the T-rail or the guard-rail, and when the car gets within a few feet of the switch the motorneer places his foot on the top of the foot-disk and forces down the rod and wheel alongside and inside of the rail, so that the wheel or arm enters between the guard-rail and the 35 T-rail when it arrives at the guard-rail, and when it reaches the switch-lever it passes between the lever and the T-rail and forces it and the end of the tongue over against the opposite side of the T-rail or guard-rail, as 40 the case may be. At the same time the motorneer may press with the side of his foot the arm of the foot-disk and slightly turn the rod and wheel, so that the scraper or brush will bear against either the side of the T-rail or the side of the guard-rail, as he desires, and clean out any dirt between the switch and along the side of the rails, as he can see 45 as he approaches the switch on which side the dirt has accumulated, and as every car that uses the switch sweeps it out it is kept practically clear of dirt. After passing the switch the motorneer takes his foot off the foot-disk and the spring raises the rod and wheel up above the rail and normally holds it there. 50 As the tongue and switch-lever are moved over by the wheel wedging in between the lever and the rail the lever strikes the opposite rail with its broadest portion, and as the tongue continues to swing up against the opposite rail the lever tilts or fulcrums on its broadest point and its free end is swung over 55 and against the opposite rail, thus setting it

in operative position to switch the tongue back. Thus in Fig. 1 the switch is closed and the free end of the switch-lever is lying 70 against the guard-rail. When a car is to be switched off the main line, the motorneer presses down the switch-thrower, and as it enters between the lever and T-rail it wedges the lever and tongue over against the guard-rail into the position shown in the dotted lines, which opens it and leaves it open, but in operative position to be closed. Consequently the first car that comes along whose motorneer wishes to keep the main track must 80 press down his switch-thrower and switch it back or close it and leave it closed and in position to be opened by the next motorneer that wishes it open.

In Fig. 7 I illustrate a modification of the 85 switch-lever, which consists of forming a round pivotal pin 32 on the under side of the central portion of the lever and extending it into a hole in the bed-plate, which makes the lever pivot on the pin, causing its point to swing 90° positively from side to side as the switch-thrower engages it between the pin and the tongue.

I also show a modification of the switch-throwing rod and scraper in Figs. 8 and 9. 95 In place of the scraper shown in Figs. 4 and 5 I use a wire brush 33 by forming a socket 33^A on the end of the scraper 30 and clamping a wire brush in it by a set-screw 34, as shown in Fig. 8.

I may also find it convenient to dispense with the wheel at the end of the switch-throwing rod and use instead a shoe 35, which preferably has a curved forward end and a rearward extension and attaches to the rod in a 100 similar manner to the yoke.

My invention is simple and durable and enables the switches to be thrown from the car without stopping and at the same time cleans the switch-spaces as it passes through them.

Having described my invention, what I claim as new, and desire to secure by Letters Patent, is—

1. The combination with the rails in a car-switch, of a laterally-springing elastic rod reciprocally journaled to and extending from above through the platform of said car to said tracks, a spring arranged to control one movement of said rod, a manually-operating foot-plate on the upper end of said rod, and having a projecting arm adapted to engage the sides of an operator's foot, a flange below said foot-plate secured to said car's platform in which the top of said rod is journaled, a 115 bracket secured to said plate and arranged loosely on each side of said rod and adapted to allow a slight turning movement to said foot-plate and rod by a side movement of an operator's foot, a suitable device at the lower 120 end of said rod for engaging said switch-lever to throw it and said switch-tongue to open or close said switch, and an elastic lever or brush attached to the lower end of said rod ar- 125 130

ranged to scrape or sweep the dirt out of said switch as said switch-throwing rod passes through it, substantially as described.

2. The combination with the rails, of the T-rail, the guard-rail, the bed-plate, the switch-tongue and the switch-lever with a switch-throwing foot operating rod secured to and arranged to be manually operated from the platform of said car, and having a portion of its length elastic enough to allow it to spring sidewise to compensate for the swaying of said car when the lower end of said rod is between the switch-rails and having said rod journaled to have a slight turning movement, a spring arranged to normally hold said rod out of engagement with said rails, a foot-plate on the top of said rod for pressing said rod against said spring down between said

rails to throw said switch-lever and switch-tongue, a suitable terminal end on said switch-rod for engaging said switch-lever, a brush secured to the switching end of said rod adapted to sweep out dirt as said rod passes through said switch, means connected with said foot-plate for manually turning said rod with an operator's foot to cause said brush to sweep the side of said rails, and means substantially as described for defining the turning movement of said rod and brush substantially as described.

In testimony whereof I affix my signature in presence of two witnesses.

CLAUDE A. DUNN.
